CLAIM

The ornamental design for the duplex clip and holder, as shown and described.

DESCRIPTION

FIG. 1 is a front perspective view of a duplex clip and holder showing our new design;
FIG. 2 is a right side view of the duplex clip and holder;
FIG. 3 is a left side view of the duplex clip and holder;
FIG. 4 is a top view of the duplex clip and holder;
FIG. 5 is a bottom view of the duplex clip and holder;
FIG. 6 is a front view of the duplex clip and holder;
FIG. 7 is a rear view of the duplex clip and holder;
FIG. 8 is a right side elevational view of the duplex clip and holder, the broken line showing of the coupled duplex clip and holder is for illustrative purposes only and forms no part of the claimed design;
FIG. 9 is a bottom plan view thereof; and,
FIG. 10 is a perspective view thereof.
